MANUFACTURE OF ORGANOLEAD COMPOUNDS

Sidney M. Blitzer and Tillmon H. Pearson, Baton Rouge, La., assignors to Ethyl Corporation, New York, N. Y., a corporation of Delaware

No Drawing. Application March 28, 1955
Serial No. 497,378

7 Claims. (Cl. 260—437)

This invention relates to a process for the manufacture of organolead compounds. In particular, this invention is directed to an improved process for the manufacture of tetraethyllead.

The process employed in present commercial practice for the manufacture of tetraethyllead has been in use for a number of years and, in general, is satisfactory. However, it has certain disadvantages which are overcome by practicing our invention. It proceeds by reacting a sodium-lead alloy, of composition controlled to correspond substantially to NaPb, with ethyl chloride according to the following equation:

With the highest yields obtained thereby, only about 22 percent of the lead present in the NaPb alloy is converted to tetraethyllead. Under conditions of best operation of this process, no one heretofore, as far as we are aware, has been able to increase this yield of tetraethyllead by even a few percent, due to the inherent limitation in yield as is apparent from the consideration of the above equation. It should be noted that in this reaction at least 75 percent of the lead originally employed is not alkylated. Thus, in this reaction, large quantities of lead must be recovered and reprocessed to NaPb alloy in order to make it economical. A further disadvantage of such a large quantity of unreacted lead is that valuable reaction space in the reaction vessel is occupied by materials which are essentially inert for the manufacture of tetraethyllead under present conditions and mode of operation.

Other processes for the production of organolead compounds, and in particular tetraethyllead, have been devised to consume the lead produced in the above equation. While such processes are satisfactory from the standpoint of lead consumption, they suffer an additional drawback in common with the present commercial process in that they require organo halide as the ethylating agent. One such process is that described in U. S. Patent 2,535,190 wherein lead as, for example, that produced in the commercial process, is treated with metallic magnesium and ethyl chloride in the presence of a catalyst preferably an alkyl ether. Thus, in this process as well as the present commercial process, the tetraethyllead manufacturing operation is restricted by the necessary balance between the metallic sodium required and the organic chlorine in the ethyl chloride.

It is therefore an object of this invention to provide a process for the manufacture of organolead compounds which overcomes the above objections to the present commercial process and those processes which have been proposed more recently as an improvement thereover. Particularly, it is an object of the invention to increase the conversion of lead to tetraethyllead above that obtained in present commercial practice without requiring the use of metallic sodium, metallic lead, or alkyl halogen compounds.

These and other objects of this invention are accom-

plished by reacting a lead halide wherein the halide has an atomic weight greater than 35, that is the chlorides, bromides, and iodides of lead, and mixed lead halides, with an organo metallic compound of group III A of the periodic table, that is boron, aluminum gallium, and indium, wherein the group III A metal is the sole metal in the metallo organic compound.

In accordance with this invention, it has been discovered that to produce organolead compounds it is unnecessary to start with a lead alloy, or in fact to employ metallic lead at all. Among the lead halides that can be employed in the process of this invention are lead chloride, lead bromide, lead iodide, lead bromoiodide, lead chloroiodide, and lead chlorobromide.

The process of the present invention can best be understood by considering the chemical equation involved. In general, the process proceeds according to the equation

where R is an organic radical and X is halogen having atomic weight greater than 35, and M represents a metal of group III A of the periodic table, namely boron, aluminum, gallium, or indium. In the preferred embodiment of this process the organic radicals are hydrocarbons and particularly are non-aromatic or aromatic. Among the non-aromatic radicals we can employ alkyl or hydrocarbon substituted alkyl radicals. In general, we prefer the lower alkyl radicals having up to about eight carbon atoms. Among the aromatic radicals which can be employed in the above reaction are included phenyl and hydrocarbon substituted phenyl radicals such as the alkaryl radicals. In general, aromatic radicals having up to ten carbon atoms are satisfactory. Thus, the compounds MR_3 may be considered alkylating or arylating agents with respect to the lead in the inorganic lead compound.

Of greatest current importance from a commercial standpoint is the manufacture of tetraethyllead by the process of this invention. This embodiment can be illustrated by reference to the following equation representing the preferred embodiment.

Illustrative of the alkylating or arylating agents which we can employ are trimethyl aluminum, trimethyl gallium, trimethyl boron, trimethyl indium, triethyl aluminum, triethyl gallium, triethyl boron, triethyl indium, tripropyl aluminum, tripropyl gallium, tripropyl boron, tripropyl indium, tributyl aluminum, tributyl gallium, tributyl boron, tributyl indium, triamyl aluminum, triamyl gallium, triamyl boron, triamyl indium, and the like up to about trioctyl aluminum, trioctyl gallium, trioctyl boron, trioctyl indium, triphenyl aluminum, triphenyl gallium, triphenyl boron, triphenyl indium, tribenzyl aluminum, tribenzyl gallium, tribenzyl boron, tribenzyl indium, tri-tolyl aluminum, tri-tolyl gallium, tri-tolyl boron, tri-tolyl indium, triphenethyl aluminum, triphenethyl gallium, triphenethyl boron, triphenethyl indium, tributylphenyl aluminum, tributylphenyl gallium, tributylphenyl boron, tri-butylphenyl indium, tri(diethylphenyl) aluminum, tri(diethylphenyl) gallium, tri(diethylphenyl) boron, tri(diethylphenyl) indium and the like. In addition to the normal alkyl aluminum, boron, gallium and indium compounds indicated heretofore, the branched chain isomers can be employed. Furthermore, mixed organo aluminum compounds can be employed to produce mixed organolead compounds. Such raw materials include, for example, dimethyl ethyl aluminum, dimethyl phenyl aluminum, dibutyl phenyl gallium, diphenyl methyl boron, and the like.

By the process of this invention, as much as 50 percent of the lead in the foregoing lead salts is directly converted to organolead, or in particular, in a commercial embodi-

ment, to tetraethyllead. The remaining portion of the lead is in a highly active form as lead metal and is ideally suited for employment in the commercial process employing sodium-lead alloy or in that which proposes the reaction of metallic lead with an alkylating agent in the presence of magnesium and a catalyst. Conversely, the lead so produced by this invention can be recycled economically to the present process by conversion to the appropriate lead salt.

Our invention is adaptable to the production of organolead compounds generally, such as tetraethyllead, tetramethyllead, dimethyldiethyllead, tetraphenyllead, triethylphenyllead and tetrapropyllead. Nevertheless, for convenience in describing our invention hereafter, specific reference will be made to tetraethyllead, the most widely known because of its use as an anti-knock agent. Whenever, in the following description, this material is referred to, it is to be understood that other organolead compounds or mixtures can be made by our process.

Likewise, aluminum triethyl is the preferred organic reactant in the process of this invention and for convenience, sometimes hereinafter the invention will be described with reference to the employment of aluminum triethyl. However, when this material is referred to, it is to be understood that the other group III A metals can be employed as the metallic organic reactant of this process.

Generally, the process of this invention is conducted as follows. Into a reaction vessel, preferably a stirred autoclave, is placed the desired quantities of organo metallic compound, for example, an organo aluminum compound, suspended or dissolved in an inert liquid carrier such as, for example, a hydrocarbon of medium boiling range. The appropriate lead salt, for example lead chloride in finely divided solid form is introduced through a hopper containing a plugcock into the autoclave while agitating to create a suspension of the lead compound in the inert liquid carrier. The connection to the hopper is thereupon closed and moderate heat is applied to the reaction vessel while continuing the agitation. Thereupon, an exothermic reaction ensues and upon reaching the desired reaction temperature, cooling is provided through a jacket in the autoclave. In contrast to other processes for the manufacture of tetraethyllead, when this invention is employed it is not necessary to provide expensive and complex reflux equipment as, by proper choice of the carrier liquid, the reaction can be conducted in a closed system. Thus, tetraethyllead can be produced without the co-presence of ethyl chloride in the closed vessel. This greatly facilitates control of the reaction and prevents the existence of an otherwise hazardous operation. After completion of the reaction, the organolead compound produced is in solution in the carrier liquid and the other products, namely the aluminum salt and metallic lead, can be removed by filtration and the organolead compound removed from the carrier by distillation.

The operation described above can be varied and it is not intended that this invention be limited to the specific sequence of addition of the reactants. For example, the organo aluminum compound can be added to a suspension of finely divided lead halide with agitation. Other modifications will be evident.

While the above operations were discussed in connection with a batch operation, they can be successfully adapted to a continuous process. In addition to applying the above operations to a continuous process, other modifications of a continuous process can be made, such as first mixing together all the reaction materials and then passing them continuously through a suitable reaction zone.

It has been indicated that the process of the present invention is conducted in the presence of an inert carrier liquid. Hydrocarbons of appropriate boiling point with respect to the organolead compound produced are satisfactory and can be chosen so as to provide a solution

of the product suitable for other applications or so that they can be readily removed by distillation at a temperature at which the organolead compound will not decompose. Other inert carrier liquids are satisfactory and where the product is a liquid such as, for example, in the manufacture of tetraethyllead, the organolead compound itself can be employed as a carrier liquid. In such an operation, economies are effected by obviating the necessity of recovery by other means than merely filtration of the co-produced solids. Another class of carrier liquids comprises the liquid amines, liquid ammonia, and ethers. The principal criterion of choice, therefore, of a carrier is the physical characteristic of the organolead compound produced, and the inertness of the liquid to the organo aluminum reactant. Certain of the aforementioned reactant carriers, while inert to the reactants, exhibit a beneficial effect on the reaction which may be considered catalytic in nature and contribute to the ease of reaction and rapidity of arriving at completion of the reaction at relatively lower temperatures and pressures.

In general, when conducting this process in the presence of a liquid carrier as above, the amount of carrier should be proportioned so as to provide adequate heat removal facilities. In general, the load on the heat transfer medium is proportional to the concentration or relative proportion of the reactants and carrier. In a batch operation, it is preferred to employ the liquid diluent in the proportion of as much as 1,000 parts per part of organo metallic reactant. In a continuous operation or in an operation provided the maximum heat transfer medium, a more concentrated reaction mixture can be employed wherein as little as equal parts by weight of carrier and organo metallic reactant are employed. In general, it has been found that a more concentrated reaction mixture provides a rapid reaction and, provided adequate heat removal means are provided, this is an advantage as the organolead product is subjected to the elevated reaction temperature for the shortest practical time, thereby minimizing thermal decomposition or undesirable side reactions.

It has been found that by increasing the ratio of the organo aluminum reactant to solvent that, other conditions remaining constant, the yield is significantly improved. Thus, when employing an aromatic solvent, increasing the molar ratio of organo aluminum to solvent ten fold in the reaction with a lead halide, a 200 percent increase in yield of organolead is obtained. Thus, by increasing the molar ratio of organo aluminum reactant to solvent from .01 to .05, the conversion based upon lead halide is increased from 12 percent to 17 percent. Similarly, at a higher concentration a corresponding conversion increase is obtained.

While it has been found that in general any inert liquid which acts as a solvent for the organo aluminum compound can be employed with good results, generally superior results are obtained when aromatic hydrocarbon solvents are employed. Not only is a more rapid reaction encountered, but the ultimate yield is considerably improved in comparison, for example, to a paraffinic hydrocarbon solvent. Among such preferred aromatic solvents are included benzene, toluene, xylene, and the liquid alkyl naphthalenes such as α -methyl naphthalene, β -methyl naphthalene, ethyl naphthalene, tetralin and the like.

The group III A metallo organic compound employed in the process of this invention can be prepared by methods well known in the art. For example, reaction between organo lithium compounds and aluminum halides produces the corresponding organo aluminum compound. Thus, aluminum triethyl can be prepared by reaction between lithium ethyl and aluminum chloride. More recently, it has been proposed to produce organo aluminum compounds by reaction between aluminum hydride and the appropriate olefin. It is not intended, however, that the scope of this invention be limited to any particular

method of producing the hydrocarbon carrying reactant.

This invention can be further understood by the following detailed working example of one method of practicing this invention as directed to the manufacture of tetraethyllead.

Example I

An autoclave equipped with internal agitation, external heating means, and external cooling means is employed having a hopper attached thereto for containing finely divided lead salt. The hopper has a plugcock at the discharge end for admission of the lead salt to the autoclave. To the autoclave are added 87 parts of toluene, agitation is commenced and 3.9 parts of lead chloride of particle size of less than $\frac{1}{16}$ inch were admitted to the autoclave. The stop cock of the hopper was closed. The autoclave is purged with dry nitrogen gas then 1.5 parts of triethyl aluminum are fed thereto. The reaction mixture, while under a nitrogen atmosphere, was maintained between 20° and 25° C. for a total reaction period of $\frac{1}{2}$ hour. The mixture was then filtered to remove solid constituents which are further processed for recovery of lead value. The filtrate was washed with an equal volume of water. The organic layer was transferred to a still for removal by vacuum distillation of the toluene and recovery of the tetraethyllead from the mixture. The conversion obtained was 46 percent of the theoretical.

Similarly, when trimethyl aluminum, tripropyl aluminum, triphenyl aluminum, tribenzyl aluminum, triethyl aluminum, and tributyl aluminum are employed in the process of the foregoing example, satisfactory yields of tetramethyllead, tetrapropyllead, tetraphenyllead, tetrabenzyllead, tetraethyllead, and tetrabutyllead are produced, respectively. Likewise, when trimethyl boron, tripropyl gallium, triphenyl indium, tribenzyl gallium, triethyl boron, and tributyl indium are employed in the process of the foregoing example, satisfactory yields of tetramethyllead, tetrapropyllead, tetraphenyllead, tetrabenzyllead, tetraethyllead, and tetrabutyllead are produced, respectively.

In general, the reaction of this process is completed within a relatively short period at elevated temperatures, but a somewhat longer time is required at lower temperatures. In general, a reaction time of between about one-half to twenty hours is employed. In particular, in the manufacture of tetraethyllead with triethyl aluminum and lead bromide, we prefer to employ a reaction time of about ten hours or less.

The pressure employed in the reaction vessel is not critical and is usually the autogenous pressure created by the carrier liquid at the temperature employed. Since organolead compounds are relatively toxic, it is desirable to employ a closed vessel in conducting this reaction which may create an elevated pressure if low boiling carrier liquids are employed.

The temperature required in the operation of the process of this invention depends to a large degree upon the nature of the products formed. It has been found that when elevated temperatures are employed, the aluminum halide produced in the reaction destroys the organolead compound produced at a rate competitive with the formation of the organolead compound. Therefore, in a batch operation wherein the contact time is relatively extended, it is preferred to maintain the reaction temperature between about -10° C. to about 30° C. Within this range, variation is possible depending upon the stability of the organolead compound produced, the degree of dilution by the inert diluent, and duration of the reaction period. In a continuous operation wherein the reaction products can be rapidly removed from the reaction zone or wherein a quenching operation can be employed so as to rapidly reduce the temperature of the reaction mixture or to destroy the aluminum halide produced, successful operation can be obtained with some-

what higher temperatures. Thus, if such means are provided, the process can be conducted successfully in the temperature range of between about -10° C. and 100° C. Conversely, in a batch operation, higher temperatures can

likewise be employed if provision is made for chemically removing the aluminum halide produced from the locus of the organolead compound. Thus, with the more stable organo aluminum compounds, polar solvents can be co-employed or complexing agents having atoms capable of coordinating with the aluminum halide produced can be successfully employed to provide successful reactions at more elevated temperatures.

While it was indicated above that, in general, a catalyst is not required for the practice of this invention, certain materials do exhibit a catalytic effect upon the reaction and, in many instances, their inclusion in the reaction provides a smoother operation. Typical of such materials are heavy metal iodides as well as iodine itself, organic iodides, certain ketones such as acetone and methyl ethyl ketone, and ethers, amines, and aromatic solvents as indicated heretofore.

The following detailed examples serve to illustrate additional specific embodiments of the present invention. However, the invention is not intended to be limited thereto.

Example II

Following the procedure of Example I, with the exception that the autoclave was sealed after adding the reactants, 1.5 parts of triethyl aluminum were reacted with 4.0 parts of lead bromide in 100 parts of n-hexane. The temperature employed was 80° to 89° C. and the reaction period was one hour. Based upon lead bromide converted to organolead, a nearly quantitative yield of tetraethyllead was obtained.

Example III

In a reactor maintained under an atmosphere of dry nitrogen, 1.5 parts of triethyl aluminum were reacted with 3.91 parts of lead chloride in 200 parts of n-hexane. Room temperature was employed and a spontaneous reaction occurred. Tetraethyllead was recovered in high yield.

Example IV

Tetrahexyllead is prepared in high yield by reacting trihexyl aluminum with lead chloride in essentially stoichiometric amounts in the presence of cyclohexane at atmospheric pressure and at a temperature of 75° to 85° C. for three hours reaction time.

Example V

Again employing the procedure of Example I, tetraphenyllead is obtained in high yield when triphenyl aluminum dissolved in benzene is reacted with lead chloride in essentially stoichiometric quantities. The temperature employed is 75° to 83° C. for a period of 5½ hours.

Example VI

Example I is repeated essentially as described with the exception that tetraethyllead is employed as the diluent and the reaction temperature is 30° to 40° C. In this instance, the process is conducted continuously by continuously feeding the triethyl aluminum and lead chloride to the reactor and withdrawing a slurry of solids in tetraethyllead from the reactor leaving a heel of tetraethyllead sufficient to maintain fluidity of the reaction mixture.

Equally good results are obtained when the corresponding and other organo compounds of gallium, boron and indium are employed in the above examples. For example, triethyl gallium, indium or boron can be reacted with lead chloride to produce tetraethyllead. Triphenyl gallium, indium or boron, preferably dissolved in a suitable solvent such as benzene can be reacted with lead bromide to produce tetraphenyllead. Other examples will be evident.

A particularly advantageous and preferred method of utilizing the process of this invention as specifically directed to a commercial method of manufacturing tetraethyllead comprises starting with free aluminum and hydriding to produce the corresponding aluminum hydride as the first stage. A second stage then comprises reacting said hydride with ethylene preferably in the presence of a solvent suitable as a carrier for the ethyl aluminum, which is thereafter reacted with the lead chloride in accordance with the foregoing description of the present invention.

We claim:

1. A process for the manufacture of hydrocarbon lead compounds which comprises reacting a hydrocarbon metallic group III-A compound wherein each hydrocarbon radical has up to about 10 carbon atoms inclusive and is selected from the group consisting of alkyl and aryl radicals with a lead halide of a halogen selected from the group consisting of chlorine, bromine and iodine.
2. A process for making alkyllead compounds which comprises reacting a lead halide of a halogen selected from the group consisting of chlorine, bromine, and iodine

with a trialkyl aluminum compound wherein each alkyl radical contains up to 8 carbon atoms inclusive.

3. A process for the manufacture of tetraethyllead which comprises reacting lead chloride with triethyl aluminum.

4. The process of claim 3 wherein the reaction is conducted in the presence of an inert carrier liquid.

5. The process of claim 3 wherein the reaction is conducted at a temperature between about -10 to 100° C.

6. The process of claim 5 wherein the reaction is conducted in the presence of an inert carrier liquid.

7. The process of claim 5 wherein said carrier liquid is toluene.
